CLAIM

The ornamental design for a toilet seat lifting handle, as shown and described.

DESCRIPTION

FIG. 1 is a top perspective view of a toilet seat lifting handle, showing my new design;

FIG. 2 is a top plan view thereof;

FIG. 3 is a side view thereof, the opposite side being of mirror-image appearance;

FIG. 4 is a bottom view thereof;

FIG. 5 is an end view taken from the bottom of FIG. 2; and, FIG. 6 is an end view taken from the top of FIG. 3.

The broken line showing is for illustrative purposes only and forms no part of the claimed design.
